By his Attorney,
Nelson R. Howard

UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

PULLING-OVER MACHINE.

1,202,261.

Specification of Letters Patent. Patented Oct. 24, 1916.

Application filed February 1, 1916. Serial No. 75,576.

To all whom it may concern:

Be it known that I, ARTHUR BATES, a subject of the King of England, residing at Leicester, Leicestershire, England, have 5 invented certain Improvements in Pulling-Over Machines, of which the following description, in connection with the accompanying drawings, is a specification, like reference characters on the drawings indicating 10 like parts in the several figures.

This invention relates to pulling-over machines and is herein shown as embodied in a machine of the type shown and described in United States Letters Patent No. 15 1,029,387, granted June 11, 1912, on application of Ronald F. McFeely.

The object of this invention is to extend the field of utility of that machine by adapting it to perform operations heretofore performed by hand or with the aid of 20 apparatus not comprised in the machine.

In the manufacture of shoes the work comes to the pulling-over machine with the upper and innersole assembled upon the last 25 and the upper connected to the innersole and usually to the last at the rear end of the heel, the upper being otherwise loose upon the last. Good shoemaking requires that the upper be firmly drawn forwardly relatively to the last, and the extent of this 30 forward pulling usually required to be made on a loose upper is such that it is the general practice in making good shoes for the operative to spindle the last and pull the upper forwardly by the use of hand pincers or, alternatively, to effect this preparatory forward pulling of the upper by the use of the apparatus shown in United States Letters Patent No. 1,139,613, granted May 18, 1915,

40 on application of Pearl J. Wentworth. The present invention provides for combining this preliminary pulling of the upper with the pulling-over operation by utilizing the toe gripper of a pulling-over machine and 45 providing an abutment suitably located with relation to the said gripper to enable the last to be fulcrumed thereon for pulling the upper, after which the upper is arranged in the side grippers of the pulling-over 50 machine and those grippers closed while the toe gripper continues to hold the upper. This fully conserves the forward pull and saves one handling of the shoe.

A feature of this invention consists in

the combination with a power-operated gripper mechanism comprising a yieldingly closed toe gripper which normally comes to rest with the jaws open, of manual means for causing said mechanism to close the jaws, and an abutment located in relation 60 to said gripper to permit the last to be fulcrumed thereon for pulling the upper.

A further feature of the invention consists in a pulling-over machine comprising power-operated side and toe grippers which 65 normally come to rest with the jaws open, of manually operated means for causing said mechanism to close the toe gripper separately, and an abutment arranged with relation to said toe and side grippers to permit the shoe last to be fulcrumed thereon for pulling the upper between the toe gripper and the last and carrying the sides of the upper into the open jaws of the side 70 grippers.

These and other features of the invention including certain combinations of parts and more important details of construction will now be described in connection with the accompanying drawings and will then be 80 pointed out in the claims.

Figure 1 of the drawings shows a side elevation of a pulling-over machine partly in section and equipped with the present improvement. Fig. 2 shows a detail of the 85 toe gripper controlling mechanism. Fig. 3 is a vertical section through the toe gripper.

The illustrative machine as a whole is constructed substantially in accordance with the disclosure in said McFeely patent and 90 comprises a sole rest 1 against which the bottom face of a shoe is adapted to be positioned between a toe gripper 2 and side grippers 4. The grippers are suspended from updraw levers pivoted on the fulcrum 95 rod 5 and connected at their rear ends with updraw cams located on the cam shaft 6 as in said patent. The machine is organized to come to rest automatically at the end of the pulling-over operation with the grippers lowered to shoe receiving position, the jaws being opened by the engagement of an abutment 8 on the gripper casing with a portion of the frame of the machine while the gripper bar 10 is forced downwardly 100 to bring the surface 12 into engagement with the outer face of the movable gripper jaws as shown in Fig. 3. A spring 13 is

arranged within the gripper casing in position to become compressed by the jaw opening movement of bar 10. When the spring is permitted to do so, it expands and forces 5 the bar upwardly, moving a closing roll 14 along the inner face of the movable gripper jaw to rock that jaw for gripping the stock. This organization of gripper mechanism is well known and does not require 10 more detailed description.

In accordance with the illustrative embodiment of this invention, the rear end of the toe gripper lever 15 is connected to its operating cam 16 through a slide 18 that 15 has a movable connection with a rod 20, the rod extending upwardly through a knuckle on the rear end of the lever 15 and carrying a spring 22 that is under compression and through which downward movement of the 20 rod is transmitted yieldingly to the lever for effecting upward movement of the gripper bar 10. The movable connection between the slide 18 and rod 20 is herein shown as comprising a block 24 secured to the lower 25 end of the rod and movable vertically in the slide, being normally upheld in the slide by a latch 25 that is carried by the slide. The arrangement is such that when the latch 25 is withdrawn from under a projection 26 on the slide the closing spring 13 is allowed to expand and lift the gripper bar 10 and the front end of lever 15, depressing the rear end of the lever together with the rod 20 and block 24. As before explained, such 30 upward movement of the gripper bar 10 effects the closing of the toe gripper jaws. The guideway within which block 24 moves 35 in slide 18 is long enough to permit all the movement required for closing the gripper jaws upon the thinnest stock presented to the machine. The latch 25 is controlled by one 40 arm of a rock-shaft 30 the other arm of which is connected by a rod 32 with a lever 34 fulcrumed at its rear end and provided 45 with a foot pedal at its front end.

In using the invention the operative presents an assembled shoe with the toe end of the upper between the jaws of the toe gripper as shown in full lines in Fig. 1 and by 50 pressure of his foot on the pedal of lever 34 withdraws the latch 25 from the projection 26 of the block 24 and thereby allows the spring 13 to close the toe gripper. For permitting the last to be fulcrumed and moved 55 relatively to the toe gripper, the toe gripper is provided on its rear face with a leg 35 that projects backwardly and downwardly into position to be engaged by the shoe bottom at a distance from the end of the toe 60 in excess of the width of the channel and feather formation of a welt shoe innersole. The location thus provided for the insole engaging face of the leg has the advantage that injury to the channel and feather formation of the insole is avoided and that it

locates the fulcrum for the last at such a distance from the gripper jaws that a long pull on the upper forwardly can be obtained for taking the slack out of a loose upper. After closing of the toe gripper has been effected 70 in response to the pedal motion, the operative swings the shoe from the full line position toward the dotted line position in Fig. 1, causing the last to fulcrum on the leg 35 and thereby effecting substantially the same 75 forward pull upon the upper which it has been customary to effect by the use of hand pincers or the apparatus of said Patent No. 1,139,613. The described rearward and upward movement of the shoe to the dotted 80 line position in Fig. 1 brings it against the sole rest 1 and locates the sides of the upper in position to be seized by the said grippers. Those grippers close upon the upper in response to pressure upon the starting treadle 85 of the machine (not shown) and thereafter the grippers and other portions of the machine coöperate to pull over the shoe as explained in the McFeely patent.

In the power operation of the machine the 90 slide 18 is moved downwardly by cam 16, and during this movement the face 27 of latch 25 engages the projection 29 of the block 24 to effect downward movement of the block and the rod 20, and the operation 95 of the updraw lever 15 for raising the toe gripper. During the return or upward movement of the slide 18 after the pulling operation, the latch 25 is restored to engagement with the projection 26 by the action 100 of a spring 31 which is shown in Fig. 1, said spring 31 also serving the purpose of a lifting spring for the pedal lever 34.

Having explained the nature of the invention and described an illustrative embodiment of the invention and how it may be used, I claim as new and desire to secure by Letters Patent of the United States:—

1. A pulling-over machine having, in combination, a power-operated gripper mechanism including a yieldingly closed toe gripper and means to bring the toe gripper to rest with the gripper jaws open, manually controlled means for closing the jaws of the toe gripper, and an abutment located in relation to said gripper to permit the shoe last to be fulcrumed thereon and rocked with relation to the gripper for pulling the upper lengthwise of the last.

2. A pulling-over machine having, in combination, a power-operated gripper mechanism including yieldingly closed side and toe grippers and means to bring the grippers to rest with the jaws open, manually controlled means for closing the jaws of the toe gripper while the jaws of the side grippers remain open, and an abutment arranged with relation to said toe and side grippers to permit the shoe last to be fulcrumed thereon for pulling the upper be- 130

tween the toe gripper and the last and carrying the sides of the upper into the open jaws of the side grippers.

3. In a pulling-over machine, the combination with power-operated toe and side grippers, of manually controlled means for causing the toe gripper to seize the upper, and a leg projecting from the toe gripper downwardly and backwardly into position to engage a welt shoe innersole inside the channel and arranged to permit the shoe last to be fulcrumed thereon for pulling the upper between the toe gripper and the last as the shoe is moved into position for the upper to be seized by the side grippers.
4. In a pulling-over machine, the combination with a toe gripper, of a last engaging abutment extending from the toe gripper downwardly and rearwardly into position for engagement with the innersole of a welt shoe at the inner side of the channel.

5. In a pulling-over machine, the combination with a power-operated gripper mechanism including a jaw closing spring, an updraw lever, a latch, and a cam through 25 which the closing spring is put under tension and held and which comes to rest with the closing spring under tension, of manually controlled means for releasing the latch to permit the spring to close the jaws. 30

6. In a pulling-over machine, gripper operating mechanism including an updraw lever, a cam slide, a block movable in the cam slide and connected to the lever, a latch pivoted in the cam slide and normally holding the block in an operative relation to the slide, and manually controlled means for operating the latch. 35

In testimony whereof I have signed my name to this specification.

ARTHUR BATES.
